UNITED STATES PATENT OFFICE.

FREDRIK LJUNGSTRÖM, OF LIDINGO-BREVIK, AND ALF LYSHOLM, OF STOCKHOLM, SWEDEN, ASSIGNEES TO AKTIEBOLAGET LJUNGSTRÖMS ÅNGTURBIN, OF STOCKHOLM, SWEDEN, A CORPORATION.

CONDENSER PLANT FOR LOCOMOTIVES.

Application filed August 17, 1922, Serial No. 582,561, and in Sweden March 16, 1922.

Condenser plants for locomotives are known in which the exhaust steam is deprived of its heat directly or indirectly by the aid of the surrounding air. Thus for instance it has been suggested to conduct the exhaust steam from the locomotive and, if desired, also from the auxiliaries of a locomotive into an air-cooled condenser, for instance connected with an accumulating liquid receptacle, the whole condenser plant being under vacuum and the steam passing through elements placed side by side, whilst air is forced about said elements either by means of fans or on account of the speed of the locomotive. It has also been suggested to discharge the exhaust steam of the locomotive into a water cooled surface condenser, the cooling water being conducted to a cooling stack situated on the locomotive, in which the water is cooled by air forced by the speed of the train through the water sprinkling down. Such condenser plants have several defects and besides they do not afford in many cases the desired result owing to leaks and excessive consumption of water. Furthermore it has proved difficult, particularly in case of recooling devices connected with cooling stacks, to force a sufficient quantity of air through the condenser and the current of air forced through the water being of considerable force has therefore blown away much water.

In condenser plants one has always sought not only to attain saving of fuel but also saving of water, so as not to be compelled to carry large reserve receptacles for water or to stop too frequently on the line for taking water. Besides it is very desirable to obtain suitable water in order to prevent formation of boiler-scale, which will not be possible if a new supply of water must be taken at stations having bad water which will form boiler-scale.

This invention relates to a condenser plant of a type in which a quantity of water is circulated without necessitating the addition of water and in which the exhaust steam of the locomotive and, if desired, also of auxiliary apparatus is condensed in one or more water-cooled condensers. The invention consists chiefly in that the cooling water with or without condensate is recooled in a recooling device cooled by air which is forced forward by means of fans.

The accompanying drawings illustrate

some embodiments of the invention. Fig. 1 shows a locomotive provided with a condenser plant constructed according to the invention, and Fig. 2 is a diagrammatic cross-section through the condenser.

Referring to Figs. 1 and 2, this embodiment is particularly applicable to locomotives provided with piston machinery. 1 designates the carriage supporting the steam boiler 2 of the locomotive, the driver's cab 3, the piston machinery 4 and the condenser 5. The cooling water is supplied to the water cooled condenser 5 through the pipe 7 and is discharged through the pipe 8 in the direction indicated by the arrows. The cooling water is conducted through the pipes 7 and 8 to and from a separate carriage 9 coupled to the locomotive and supporting a recooling device. The two carriages being movable in relation to each other, said pipes are provided with articulated couplings 10 and 11. One of said cooling water pipes, for instance 8, is connected with a pump 12 effecting circulation and pumping up the water to a distributing pipe 13 extending along the recooling device. From this pipe the water, while being cooled, flows down to both sides through the elements 14 and 15 shown in Fig. 2 to the collecting pipes 16 and 17, from which it flows to the receptacle 18 situated beneath the cooling device. The cooling air is forced upward by the fans 19 which in the embodiment shown are located beneath the cooling elements 14 and 15 of the recooling device but above the liquid receptacle 18. As shown, the fans are mounted on the receptacle 18; they may however be arranged in other manner. The fan or fans which may be of any number are actuated by a common shaft 20 connected with a turbo-aggregate 21 provided with a toothed gearing but may also be driven in other manner. The turbine 21 is provided with a separate condenser consisting in the present case of a surface-condenser 22 supplied with cooling water directly from the cooling elements. To cause the cooling water supplied to the condenser 22 to pass first the cooling elements, the distributing pipe 13 is divided by means of a partition 14 so that the water will first flow downwards through one or more cooling elements 23 to the left of the partition wall to the collecting pipe 16 (17) which has a partition wall to the left of these elements and hence upwards

through one or more elements 24 placed to the right of the partition wall 14¹ to that part of the collecting pipe 13 which lies behind said partition wall. From this part of pipe 13 the water will then flow to the condenser 22. In this case the recooling device is placed on a separate carriage, but the whole locomotive-aggregate may also be placed on the same carriage. It is however most suitable, particularly in case of large locomotives to locate the locomotive-aggregate on two carriages, each carriage thereby not being too long, which would make the passage of the locomotive through curves or turntables difficult.

15 Modifications of this plant may be imagined. Thus water may for instance pass from the pump 12 through the condenser and the cooling elements in other manner, and the condenser 5 which in the present embodiment is constructed as a surface condenser of known type, may be of any other kind, as for instance an ejector condenser, a wet air-pump or any other type of mixing condenser, in which case the condensate is entrained through the conduit 8 and the recooling device. The latter may be influenced by any pressure, particularly in case of only cooling water passing through the same; atmospheric pressure is however most suitable, since in such case leaks arising for instance in the cooling elements will not affect the capacity of the condenser. The embodiment shown is not, of course, confined to locomotives of piston type, since said machinery 30 may for instance consist of a steam turbine with or without toothed gearing.

35 What we claim as new and desire to secure by Letters Patent of the United States is:—

1. In a condenser plant for locomotives and the like, a condenser, means for conducting exhaust steam to the condenser, a fluid container, means for passing fluid from said container directly through said condenser, to condense the exhaust steam therein, and for returning the heated fluid to said container, cooling apparatus and means for conducting fluid from said container directly to said cooling apparatus to be cooled and returning the cooled fluid directly to said container. 50

2. In a condenser plant for locomotives and the like, a condenser, a fluid container, cooling apparatus, a fan for blowing cooling air through said cooling apparatus, means for circulating cooling fluid from said container directly through said condenser, and means for circulating the fluid from said container directly through said cooling apparatus. 55

3. In a condenser plant for locomotives and the like, a condenser, a fluid container and a cooling apparatus, and means to circulate the fluid in said container in parallel through the condenser and the cooling apparatus. 60

4. In a condenser plant for locomotives and the like, a condenser positioned on the engine section, a fluid container and a cooling apparatus positioned on a trailer, and means to circulate the fluid in said container in parallel through the condenser and the cooling apparatus. 65 70

In witness whereof we have hereunto set our hands.

FREDRIK LJUNGSTRÖM.
ALF LYSHOLM.
